UNITED STATES PATENT OFFICE.

WILLIAM SCARLETT, OF AURORA, ILLINOIS.

BIER.

Specification of Letters Patent No. 30,251, dated October 2, 1860.

To all whom it may concern:

Be it known that I, WILLIAM SCARLETT, of Aurora, in the county of Kane and State of Illinois, have invented certain new and useful Improvements in Biers; and I do hereby declare that the following is a full, clear, and exact description thereof, reference being had to the accompanying drawings, in which—

10 Figure 1, is a side elevation, the red lines showing the coffin partly lowered. Fig. 2 is a plan view with the parts in position for use, and Fig. 3 is a vertical section showing the coffin in the bottom of the grave and released by the action of the mechanism.

Similar letters of reference indicate like parts in all the figures.

As burials are usually conducted much annoyance frequently occurs from the want 20 of uniformity in lowering a coffin into the grave, and the difficulty of removing the cords or straps by which it has been lowered, it often being necessary for some person to descend into the grave for that purpose.

My invention is designed to remedy this evil, and afford a ready means of lowering the coffin by the operation of a single crank, in such a manner that all parts must move 30 at equal velocities; and also to readily remove the supports by the same means.

To enable others skilled in the art to make and use my invention, I will proceed to describe its construction and operation by the 35 aid of the drawings and of the letters of reference marked thereon.

A is a frame work with handles, *a*, *a*, for convenience of carriage, and legs *a'*, *a'*, upon which it stands. B, B' are windlasses at 40 each end of A. B has a crank, *b*, by which it may be turned, and a ratchet wheel *W*, and pawl *w* for holding it from rotating when required. B' is driven by means of cords L, L', from B, the cords winding off 45 one and on the other in opposite directions, so as to give B' a motion equal to but opposite from that of B. B' may be driven by belts, gears, etc., in lieu of by the cords L, L', or by any other means which will insure 50 its moving at the same velocity with B.

Cords, C, C, are wound upon both B and B', as represented, in such a manner that when B is turned in one direction they are unwound from both, and in the opposite direction they are wound up on both, so that the 55 middle points of the cords, C, C, are always

at equal distances from B and B'. These cords, C, C, pass over rollers, F, F, which are adjustable in the frame A so that their positions may be made to conform to the 60 length of the grave.

D, D, are two supports, extending between the longitudinal cords C, C, and adapted to slide thereon, for the double purpose of being adjusted to the different 65 sizes of coffins and of being slid out from underneath the latter, when it is properly deposited in the grave. Straps or cords E, E, extend from D, D, to windlasses B, B', and wind thereon in the same direction as 70 the cords C, C, as shown in Fig. 1. These straps E, E, are shorter or make fewer turns around B, and B', than C, C, so that by a continued rotation of B, B', the cords or straps E, E, become unwound and commence 75 to shorten by winding in the opposite direction before C, C, are fully unwound. This effect is shown in Fig. 3.

The operation of my improved bier is as follows: The rollers, F, F, are adjusted to 80 the length and the cords C, C, to the width of the grave, and the crank *b* turned so as to tighten the cords C, C. The cross supports, D, D, are then adjusted so that the ends of the coffin will rest thereon, and the whole is 85 in the position shown by the dark lines in Fig. 1. The coffin M being placed in the position there shown, and the apparatus placed over the grave, the crank *b* is actuated in the direction of the arrow. This 90 operation turns B, and B' and thus unwinds the cords, C, C, and the straps E, E, and lowers the coffin gradually and evenly. When the coffin has arrived at the bottom of the grave, the rotation of crank B is not 95 stopped but is continued until the straps, E, E, have wound in the opposite direction sufficiently to tighten them. In this condition a little further motion of *b* in the same direction withdraws the supports D, D, 100 from underneath the coffin, and as C, C, are not beneath the coffin at any period, but only extended along each side, it is now released. The motion of *b* is next reversed, and the parts adjusted in position for the next sad 105 duty.

It is not essential to the usefulness of my invention that the several parts shall be constructed and arranged in the precise manner herein shown, as many modifications 110 thereof might be employed without altering the nature or efficiency thereof. For ex-

ample, the withdrawal of the supports D, D, may be accomplished by means of a separate windlass and crank, or by simply pulling upon the cords or straps, E, E, by hand, but 5 the plan herein shown is simple and convenient and, I think, the best for the purpose.

Having now fully described my invention, what I claim as new therein, and desire to 10 secure by Letters Patent, is—

1. In biers constructed with windlasses for lowering the coffin, the arrangement of the longitudinal cords C, C, and cross supports, D, D, adapted to slide thereon, sub-

stantially in the manner and for the purposes herein set forth.

2. So arranging the cords C, C, and straps, E, E, or their equivalents, upon the windlasses, B, B', that a continued rotation of the latter lowers the coffin and then disengages the sliding supports, D, D, or their equivalents, therefrom, substantially in the manner above specified.

WILLIAM SCARLETT.
